US0D1056319S

(12) **United States Design Patent** (10) Patent No.: **US D1,056,319 S**
(45) Date of Patent: ** Dec. 31, 2024

(54) **LAMP**

(71) Applicant: **VIBIA LIGHTING, S.L.U**, Gavà (ES)

(72) Inventor: **Meike Harde**, Mülheim (DE)

(73) Assignee: **VIBIA LIGHTING S.L.U**, Gavà (ES)

(**) Term: **15 Years**

(21) Appl. No.: **35/518,010**

(22) Filed: **Mar. 31, 2023**

(80) **Hague Agreement Data**

Int. Filing Date: **Mar. 31, 2023**

Int. Reg. No.: **DM/230518**

Int. Reg. Date: **Mar. 31, 2023**

Int. Reg. Pub. Date: **Aug. 4, 2023**
